L. J. BROWN

PIN LOCKING MEANS

Filed June 1, 1926

UNITED STATES PATENT OFFICE.

LLOYD J. BROWN, OF EVANSTON, ILLINOIS.

PIN-LOCKING MEANS.

Application filed June 1, 1926. Serial No. 112,992.

My invention relates to an improvement in means for locking connecting pins in place and more particularly as a safety device for the connecting pins of brake beams 5 employed in railroad equipment.

The object of my invention is to provide an inexpensive device in which certain portions are reenforced against improper flexure and distortion; that is to say my invention is intended to overcome certain objections encountered in the type of device here in question; the features of the invention and its advantages being readily comprehended from the detailed description of the 15 accompanying drawing, wherein:

Figure 1 is a plan view of a portion of a connecting rod and brake lever pivotally connected together by means of a connecting pin which is provided with my improved locking means.

Figure 2 is a cross-sectional view taken substantially on the line 2—2 of Figure 1.

Figure 3 is a plan view of a sheet metal blank cut and formed to produce my improved locking means.

Figure 4 is a perspective view of the blank formed up into shape ready for application.

My invention refers to the type of safety device disclosed in United States Letters 30 Patent No. 1,338,317, issued to John McMullen; my invention involving improvements in a device of the type mentioned adapted to overcome certain weaknesses and objections inherent in a device of the type in question.

My improved means is intended to be formed out of sheet metal cut to a predetermined size and length, namely to provide the elongated rectangular sheet or blank 10 shown in Figure 3 and provided at one end 40 with a pin-receiving opening 11. The blank 10, throughout a predetermined distance and at the apertured end thereof, through the action of suitable dies, is provided with corrugations indicated at 12 which are prefer-

ably arranged in the diagonal or slanting manner clearly shown in Figures 3 and 4 so as to extend at an angle to the edges of the sheet or blank and therefore at an acute angle to the bend 13 in the blank whereby 50 the lower leg or apertured portion 14 is formed and the partially corrugated and partially plain surfaced upstanding leg or portion 15 is provided. The corrugations 12 are formed in the blank 10 so as to ex-

tend to a point beyond the bend 13 in the 55 blank, namely throughout a portion of the upstanding leg 15, as clearly shown in Figures 2 and 4.

When the blank 10 is bent into the shape shown in Figure 4, the juncture between the 60 legs 14 and 15, namely at the bend 13, is provided with a suitable number of reenforcing ribs 16 formed by means of dies or in any other suitable manner with the ribs disposed within the angle defined by the legs 65 14 and 15.

The device, as disclosed in Figure 4, shows the article of manufacture in its commercial form ready for application to a connecting pin. In the particular exemplification disclosed in the drawing, I show my improved means applied to the connecting pin 17 disposed through the bifurcated end of a connecting rod 18 and a brake lever 19 disposed between the bifurcations of the connecting 75 rod 18. Connecting pins of the type in question have usually been secured in place by ordinary cotter-pins disposed through a suitable opening formed in the tail end of the connecting pin. It has been found in 80 practice that the workmen frequently fail to properly spread the cotter-pins after insertion or fail to insert a cotter-pin through the aperture in the connecting pin, with the result that the connecting pins soon are displaced, and the connecting bars and levers 85 become disconnected and derailments or serious accidents likely to be encountered. Furthermore, cotter-pins frequently become battered down or sheared off in the constant 90 operation of the elements connected by the connecting pin. In the use of my improved means, it is evident that cotter-pins need not be employed and that therefore the operation of providing the connecting pins with 95 suitable holes can also be done away with; while at the same time shorter connecting pins may be employed.

My improved means, in the form shown in Figure 4, is readily applied to equipment 100 in service by inserting the leg 14 intermediate of one fork or bifurcation of the connecting rod 18 and the lever 19, aligning the opening 11 in the leg 14 with the respective openings in the bifurcations of the connecting bar and the intermediate lever 19, after 105 which the connecting pin 17 is inserted into place through the registered apertures of

the connecting bar, locking means and lever; it being understood, of course, that the leg 14 is to be inserted at the side of the connected elements through which the connecting pin is introduced so that the upstanding leg 15 of my improved means will be disposed toward the side of the connected elements on which the head of the connecting pin is located.

10 After the positioning of the locking device as just described, the upper or free end of the upstanding leg 15 is then bent down across the head of the connecting pin so as to have the free end of the leg 15 in close proximity to the head of the connecting pin and therefore substantially parallel with the lower apertured leg 14 of the device. As is apparent from the construction shown in Figure 2, the connecting pin 17 will be 15 locked in place against accidental longitudinal movement.

The device is made of suitable sheet metal permitting the bending or flexing of the leg 15; such bending taking place at a 20 point slightly removed from the corrugations 12 as shown in Figure 2. With the blank provided with the corrugations 12, the lower leg 14, namely the portion disposed intermediate of one fork or bifurcation of 25 the connecting bar and the lever 19, will be stiffened against flexure and distortion which otherwise would result during the bending of a portion of the upstanding leg 15 across the end of the connecting pin. By 30 providing the device with the reenforcing ribs 16 within the angle defined by the lower leg 14 and upstanding leg 15 it is also apparent that any distortion or improper bending at the juncture between the lower leg 14 and upstanding leg 15 during the 35 final bending of the portion of leg 15 across the head of the pin will be impossible; while at the same time fracture of the device at the bend 13 by repeated applications of the 40 device or rather bending of the free end of the upstanding portion 15 when it is desired, for any reason, to remove the connecting pin, will be prevented. As is clearly apparent from the construction shown, 45 removal of the connecting pin may be readily accomplished by bending the end of leg 15 upwardly in Figure 2 sufficiently to clear the head of the connecting pin; in other words, application of my improved locking 50 device may not only be readily accomplished, but removal of the locking pin when occasion requires can also be easily made and repeated use of the locking device had.

As shown in Figure 2, the corrugations 55 12, in addition to being arranged throughout the entire apertured lower leg 14, are made to extend merely throughout a part of the adjoining upstanding leg 15 so as to be slightly removed from the point where the 60 upstanding leg is to be bent back across the

head of the pin, in order that bending of the upstanding leg 15 may be readily accomplished without fracturing the blank during repeated bending operations.

As locking devices of the general type 70 here in question must be of comparatively thin sheet metal because of the small amount of play, to wit about one-eighth of an inch, between the fork of the connecting rod and the brake lever, it is evident that distortion 75 of the thin sheet metal is very apt to occur during application of the device.

Any bending or even slight distortion of the device and especially of the apertured pin receiving leg is quite objectionable 80 because it will interfere with the easy and proper operation of the brake mechanism and is apt to cause the lever to bind. A condition of this sort is not only undesirable 85 but may be rather serious, especially when such condition is encountered on a number of the brake operating levers of a train of cars, as it not only hampers the release of both air and hand brakes but frequently induces a binding of the brake mechanism, 90 causing the wheels to slide and become flat in addition to producing excessive wear on the brake-shoes. The trueing or replacement of wheels is, of course, quite expensive; while the undue wear on the brake-shoes necessitates constant adjustment of the 95 brake levers to provide proper brake operation.

My invention is designed to overcome 100 these serious objections, as well as to obviate the necessity of constant adjustments and replacements and therefore tends toward a great saving of time and expense; as the reenforcement of the apertured portion of the device as for example by means of undulations or corrugations, either obliquely 105 or longitudinally, will prevent metal distortion between the connecting rod 18 and the brake lever 19; while improper flexing or bending at the juncture between the two 110 portions of the device is not only prevented by properly arranged corrugations, but also by the reenforcing ribs or upset portions 16. 115

As an exemplification of my invention I have shown the undulations or corrugations arranged obliquely to the longitudinal edges of the blank, but it will be understood that they may be differently arranged relative to the longitudinal edges and the extent thereof may be varied without, however, departing 120 from the spirit of my invention.

What I claim is:

Locking means of the character described, composed of a blank of sheet metal provided with a plurality of corrugations disposed transversely of the blank at an angle to the peripheries thereof, said corrugations extending throughout a predetermined length of the blank while the opposite end of the blank is provided with a plain surface, the 125 130

corrugated end of the blank being provided with a pin receiving aperture, the corrugated end of said blank at a predetermined point intermediate of the aperture and the opposite end of the blank being bent so as to provide a pair of legs or portions disposed at right angles to each other, the junc-

ture between the legs or portions, within the angle defined thereby, being provided with reinforcing ribs disposed lengthwise, while the plain surfaced portion of one of said legs is bent into parallel spaced relation with the apertured leg. 10

LLOYD J. BROWN.
